VALUABLES TRANSFERRING APPARATUS

Walter Swiech, Chicago, Ill., assignor of nine-twentiths to Chester A. Borys, Cicero, Ill.

Application October 26, 1944, Serial No. 560,485

11 Claims. (Cl. 232—1)

1
The present invention relates to valuables transferring apparatus and has for its object the provision of a device whereby all sorts of valuables including cash, etc., may be transferred or delivered without affording an opportunity for direct handling thereof by persons other than those directly charged with receiving the same.

A still further object of the present invention is the provision of a valuables box or container, which broadly may be either a cash box or a valuables carrying truck or the like, with means thereon provided whereby the container may be affixed to the wall in the place of ultimate delivery and where the container may be opened for the purpose of either removing therefrom or placing thereinto the valuables.

A still further object of the present invention is the provision of a suitable mechanism in conjunction with a wall for engaging the valuables carrying container whereby the latter may be held firmly in position preparatory to removal therefrom or depositing thereinto the valuables.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application and in which like designating characters refer to corresponding parts throughout the several views:

Fig. 1 is a perspective view of a valuables carrying container;

Fig. 2 is a cross-sectional view through the wall, with a side elevational view of the valuables container engaging device, with a side view of the container in an operative position;

Fig. 3 is a front elevational view of the valuables container engaging device;

Fig. 4 is a side elevational view of a latching device constituting a part of the valuables container engaging device;

Fig. 5 is a cross-sectional view on line 5—5 of Fig. 3;

Fig. 6 is a front elevational view of a pawl and ratchet device for opening the latches preparatory to the removal of the container; and

Fig. 7 is a side elevational view of said pawl and ratchet device.

Referring in detail to the present drawing there is shown therein container 10, preferably constructed in the form of a rectangular box, and which container may be either a cash box or a

2
body of a valuables carrying truck, or the like. At its one end said container 10 is provided with door 11, which affords the only communication into the container, and which is swingable upon hinges at the lower edge thereof, and is further provided with lock 12.

Rigidly affixed at the upper corners and at the same end of container 10 is a pair of male locking or coupling members 13.

10 Wall 14 has an opening 15 made therein, and along the outer face of said wall 14 said opening is closed by means of plate 16. At the lower portion said plate 16 is provided with opening 17 which is adapted to receive a swingable closure 18, which normally closes said opening 17.

20 Means for engaging the locking or coupling members 13 when container 10 is brought in contact with the outer face of plate 16, includes a pair of spaced latches, generally indicated by 19, and each includes bar 20 from the ends of which a pair of arms 21 upwardly projects. Each of said arms 21 is provided with a longitudinal slot 22 within which cross bars 23 are receivable and within which the same are adapted for vertical shifting movement. The ends of said cross bars 23 project beyond the outer faces of said arms 21, and are engaged by coil springs 24, the opposite ends of said coil springs 24 being rigidly attached to said plate 16. Said coil springs 24 normally urge said cross bars 23 downwardly.

25 Plate 16 is further provided with openings 25 which are substantially in alignment with the lower edges of said cross bars 23. Said locking or coupling members 13 on their outer ends and 30 along their upper portions are tapered so that when container 10 is brought towards plate 16, said coupling members 13 pass through openings 25 and the tapered ends thereof strike the lower edges of said cross bars 23, raising the latter 35 against the action of coil springs 24, until the adjacent end of said container 10 is in contact with the outer face of plate 16. This causes cross bars 23 to shift into a downward direction within slots 22 and make contact with shank of coupling member 13, transversely of the hooked end portion of coupling member 13, as is clearly seen in Fig. 5.

40 For the purpose of disengaging cross bars 23 from coupling members 13, a suitable pawl and ratchet device, best shown in Figs. 6 and 7, for shifting cross bars 23 in the upward direction is provided and includes drum 26 which is rigidly set upon axle 27, one end of which is set within plate 16, as is seen in Fig. 7, and the other end of which passes through U-shaped plate 28 and

carries crank wheel 29 with an operating handle 30. The rear end of said drum 26 has flange 31 and the front end carries ratchet wheel 32, which is engaged by pawl 33 pivoted on pin 34 which is set in plate 28. The outer end of pawl 33 is provided with a short string 35 by means of which pawl 33 may be manually brought out of engagement with ratchet wheel 32. Plate 28 is provided with flanges 36 through which a plurality of screws 37 pass for rigidly affixing the pawl and ratchet device to plate 16.

Affixed to plate 16 on one side of drum 26 and on a horizontal plane substantially running through the uppermost point of the periphery of said drum 26 is a pulley 38. A similar pulley 39 is affixed to plate 16 on the opposite side of drum 26 and which is substantially on a plane running along the lowermost point of the periphery of drum 26. Cord 40 affixed by one of its ends to drum 26 passed over pulley 38 connects by its opposite end with one of cross bars 23, while cord 41 connected by one of its ends with drum 26 and passed over pulley 39 connects with the other of cross bars 23. Said cords 40 and 41 connect their respective cross bars 23 and substantially centrally thereof, as is seen in Fig. 3. When drum 26 is rotated by means of handle 30 into a clockwise direction, after first disengaging pawl 33 from its engagement with ratchet wheel 32, both cords 40 and 41 will become wound up upon drum 26, thereby shifting said cross bars 23 in an upward direction from their engagement with coupling members 13, thereby freeing said coupling members 13 and permitting their withdrawal through openings 25 in plate 16, and thereby permitting removal of container 10 from said plate 16 and wall 14. This upward shifting movement of cross bars 23 is of course accomplished against the action of springs 24. When said container 10 is removed the manual hold upon handle 30 may be then released and springs 24 will retract drum 26 and cords 40 and 41 to their normal position, pawl 33 simply riding upon teeth of ratchet wheel 32 when the latter is rotated in a counter-clockwise direction, for bringing said cross bars 23 into their normal position.

From the hereinabove description it will be seen that when container 10, with its door 11 locked, is brought to the position shown in Fig. 2 with its coupling members 13 engaged by latches 19 a person in authority on the inside of wall 14 opens closure 18, applies key to lock 12 and thereby opens door 11, swinging the latter to the horizontal position and through opening 17, and thereby is given access into container 10 either for removing therefrom or placing thereto cash or valuables. When this operation is completed the person in authority swings door 11 for closing the same, thereupon locks lock 12 withdrawing the key therefrom, closes closure 18, and thereupon pulls upon string 35 for disengaging pawl 33 from ratchet wheel 32 and operates handle 30 for revolving drum 26 into a clockwise direction for shifting cross bars 23 upwardly, for freeing coupling members 13 from their engagement with said latches 19. Simultaneously a person outside of wall 14 carries away container 10. As stated, said container 10 may be driven by motive power to or away from wall 14 and when a truck is used it is assumed that wall 14 is an outer wall to which a truck may be backed up. If a truck is used, the rear end thereof will be where door 11 is placed.

From the hereinabove description it will be seen that the system of handling valuables and

permitting direct access thereto only by person in authority may be used for transferring money, pay rolls, etc., thereby minimizing the chances of theft and robbery, because the direct handlers of container 10 would have no keys to the same, for the keys would be with persons in the shipping office and the receiving office.

The system and the apparatus herein shown and described can be installed in banks, department stores, factories handling large pay rolls, etc., and may likewise be used by concerns transporting money and other valuable in armoured trucks.

While there is described herein a preferred embodiment of the present invention, it is nevertheless to be understood that minor changes may be made therein without departing from the spirit and scope of the invention as claimed.

What I claim as new is:

1. In combination with a wall having an opening, a container, a door in the latter, and means in said wall for locking engagement with said container in contact with one side of said wall, access into said container from the opposite side of said wall being had through said opening and said door when said container is in contact with said wall.

2. In combination with a wall having an opening, a container, a door in one face of said container, a locking member extending from said face of said container, said opening and said door being in alignment when said container is brought in contact with said wall, and means in said wall for engaging said locking member when said container remains in contact with said wall, access into said container being had through said opening and said door when said container remains in contact with said wall.

3. In combination with a wall having an opening, a container, a door in one face of said container, a coupling member extending from said face of said container, said opening and said door being in alignment when said container is brought in contact with said wall, and disengageable latching means in said wall for engaging said coupling member when said container remains in contact with said wall, access into said container being had through said opening and said door when said container remains in contact with said wall.

4. In combination with a wall having an opening, a container, a door in one face of said container, a locking member extending from said face of said container, said locking member being adapted to enter said wall when said container is brought in contact therewith, and means in said wall for engaging said locking member for suspending said container upon the wall and for maintaining the same in a rigid engagement therewith, access into said container being had through said opening and said door when said container remains in contact with said wall.

5. In combination with a wall having an opening, a container, a door in one face of said container, a coupling member extending from said face of said container, said coupling member being adapted to enter said wall when said face of said container remains in contact with said wall, a cross bar in said wall, said cross bar engaging said coupling member when the latter remains within said wall, access into said container being had through said opening and said door when said container remains in contact with said wall, and means for disengaging said cross

bar from said coupling member preparatory to removing said container from said wall.

6. In combination with a wall having an opening, a container, a door in one face of said container, a coupling member extending from said face of said container, said coupling member being adapted to enter said wall when said face of said container remains in contact therewith, a cross bar in said wall, a coil spring in engagement with said cross bar and said wall for maintaining said cross bar in engagement with said coupling member, said opening and said door being in alinement for providing access into said container when the latter remains in contact with said wall, said coupling member and said cross bar being adapted to maintain said container suspended upon said wall and in contact therewith, and means for shifting said cross bar away from said coupling member against the action of said spring for disengaging said cross bar from said coupling member preparatory to the removal of said container from said wall.

7. In combination with a wall having an opening, a container, a door in one face of said container, a coupling member extending from said face of said container, said coupling member being adapted to enter said wall when said face of said container remains in contact therewith, a cross bar in said wall, a coil spring in engagement with said cross bar and said wall for maintaining said cross bar in engagement with said coupling member, said opening and said door being in alinement for providing access into said container when the latter remains in contact with said wall, said coupling member and said cross bar being adapted to maintain said container suspended upon said wall and in contact therewith, a drum upon said wall, and a cord connecting with said drum and said cross bar, said cord being adapted to be wound up upon said drum upon actuation of the latter for the purpose of shifting said cross bar against the action of said spring for disengaging the same from said coupling member preparatory to the removal of said container from said wall.

8. In combination with a wall having an opening, a container, a door in one face of said container, a coupling member extending from said face of said container, said coupling member being adapted to enter said wall when said face of said container is brought in contact with said wall, and a disengageable latching means in said wall for engaging said coupling member when the latter remains within said wall, access into

said container being had through said opening and said door when said container remains in contact with said wall.

9. In combination with a wall having an opening, a closure within said opening, a door in said closure, a container, a door in said container, the two doors remaining in alinement with said container in contact with one face of said closure for providing access into said container from the opposite face of said closure, and interengaging means between said closure and said container for maintaining the same in contact with said closure.

10. In a system of transporting valuables and delivering the same to a receiving station without giving the person transporting an opportunity to directly handle the valuables transported, said receiving station having a wall with an opening therein, a valuables receiving container, a door in said container, a lock in said door for locking valuables in said container at the forwarding station, and means in said wall for disengageably locking said container to said wall with the former in contact with the latter, the valuables in the container being adapted to be removed therefrom through said opening in said wall on opening said door by a person in charge of said receiving station when said container is in contact with said wall.

11. In combination with a wall having an opening, a door in said opening, a container, a door in said container, the two doors remaining in alinement when said container is brought in contact with one face of said wall for providing access into said container from the opposite face of said wall, and interengageable means connecting said wall with said container for maintaining the same in contact with said wall.

WALTER SWIECH.
